UNITED STATES PATENT OFFICE.

FRANK YOKEL, OF BUFFALO, NEW YORK, ASSIGNOR TO MARKEL ELECTRIC PRODUCTS, INC., OF BUFFALO, NEW YORK, A CORPORATION OF NEW YORK.

DESIGN FOR A WALL PLATE FOR ELECTRIC-LIGHT FIXTURES.

Application filed November 23, 1928. Serial No. 28,997. Term of patent 3½ years.

To all whom it may concern:

Be it known that I, FRANK YOKEL, a citizen of the United States, residing at Buffalo, in the county of Erie and State of New York, have invented a new, original, and ornamental Design for Wall Plates for Electric-Light Fixtures, of which the following is a specification, reference being had to the accompanying drawing, forming part thereof.

In said drawing:

Figure 1 is a front elevation of a wall plate

for electric light fixtures showing my new design. In this figure half of the wall plate is shown in full lines and the other half in outline in dot and dash lines to indicate a repetition of the pattern.

Figure 2 is a side elevation of the same.

I claim:

The ornamental design for a wall plate for electric light fixtures, substantially as shown and described.
